OSCAR H. PIEPER AND ALPHONSE F. PIEPER, OF ROCHESTER, NEW YORK.

X-RAY APPLIANCE.

Application filed November 21, 1924. Serial No. 751,219.

This invention relates to X-ray appliances such, for example, as the variety in which the X-ray tube is flexibly supported on a tube stand for adjustment to different positions 5 about an object to be treated, as desirable, for example, in dental work, one object of the invention being to provide such an apparatus with efficient guard means for the high tension portions of the tube for eliminating danger to the patient and operator during the use of the same. More specifically, it is an object of the invention to provide improved apparatus of this character embodying guard means comprising both an insulating portion 10 and a grounded metal portion spaced from the first portion to preserve a safety air gap. A further object is to provide an adjustably supported tube of the type having a combined heat radiating means and high tension terminal at one end thereof, with simple and practical means for guarding the said tube portions with a casing of insulating material and at the same time provided for ventilation of the heat radiating means. 15

To these and other ends the invention resides in certain improvements and combinations of parts all as will be hereinafter more fully described, the novel features being pointed out in the claims at the end of the specification. 20

In the drawings:

Figure 1 is an elevation of an apparatus embodying the present invention;

Figure 2 is an enlarged sectional view on the line 2^a—2^a in Figure 5;

Figure 3 is an enlarged sectional view on the line 3^a—3^a in Figure 4;

Figure 4 is an enlarged elevation of the tube assembly and supporting means partly 40 in section;

Figure 5 is a top plan view of the same;

Figure 6 is an end view of the guard means as seen from the right in Figure 4, and

Figure 7 is a sectional view of the same on the line 7^a—7^a in Figure 4.

Similar reference numerals throughout the several views indicate the same parts.

The invention is embodied in the present instance in conjunction with an X-ray apparatus particularly suitable for dental work such as disclosed in our copending application for Letters Patent Serial No. 491,903, filed August 13, 1921, for unitary apparatus for projecting light rays, and comprising generally, as shown in Figure 1, an X-ray

tube 10 supported in a frame 11 sliding horizontally in a substantially rectangular metal yoke 12 pivotally supported at 13 between spaced arms 14 of a supporting member 15. The latter is pivotally mounted as at 16 on the end of a depending arm section 17 pivotally connected in turn at 18 to one of a pair of telescopically adjustable arm sections 19. The latter are pivotally supported on the upper end of a standard 20 telescoping vertically in a portable cabinet 21 for the high tension transformer 22, rheostat switches and other electrical operating means, as fully described in our said copending application so that a more detailed description herein appears unnecessary. Cabinet 21 is adapted to be positioned beside or behind a surgical chair with the standard arm overhanging the patient and flexibly supporting the tube for universal adjustment so that it may be quickly and easily arranged in any desired position about the object to be treated. 70

The invention may be employed in combination with various types of X-ray tubes, that at present preferred being of the variety 80 having its ray projecting portion at one end and its high tension anode terminal 23 at the other, as shown in the drawings, with an intermediate tube holding frame 11, as described comprising spaced collars clamped 85 against opposite sides of an enlarged portion of the tube by means of bolts 24. One of these collars is arranged to slide horizontally between guide-ways 25 formed by the upper and lower sides of the yoke 12 in one of the 90 adjusting movements of the tube.

The high tension terminal 23 of the tube is connected by a conductor 26 with the high tension terminal of transformer 22 in the cabinet, the conductor being supported on struts 95 27 and 28 on the stand and passing down an insulating post 29 for the purpose of maintaining the same in substantially spaced relation with the stand and so far as possible at the opposite side of the stand at all times from 100 the patient and operator. At 30 are the low tension connections between the operating means in the cabinet and the tube. In the present instance also the anode terminal carries heat radiating means in the form of a 105 series of flanges or fins 31 for dissipating the generated heat. The guard means for protecting the operator and patient against shock from the high tension connections in all positions of the tube is combined in the present 110

instance with a tube of the above variety and will now be described.

The guard means is of a double nature comprising a portion of insulating material in the form of a casing partially enclosing the high tension terminal and also a grounded metal portion arranged exteriorly of the first portion and at a substantial distance therefrom to maintain an effective air gap.

10 The first mentioned portion of the guard is in the form of a hollow substantially semi-cylindrical body 32 of suitable insulating material or composition such as can be readily molded in manufacture into the desired shape, 15 as well understood in the art. This guard is proportioned and arranged so that its walls completely enclose the high tension terminal and heat radiating means at the end of the tube on all but the upper side which is farthest removed from the operator and patient in the manipulation of the tube and the guard may be conveniently supported in such position by being provided with clamping means for mounting it directly on the adjacent tube 20 end. For this purpose the guard adjacent the tube has a contracted extension 33 proportioned to fit the lower side of the tube as shown. A semi-circular strap 34 also of insulating material embraces the upper side of 25 the tube and is detachably secured at its ends to the guard portion 33 by means of screws 35 forming a split yoke by which the guard may be securely clamped in position on the tube, so as to effectively protect objects against contact with or undue proximity to the high tension portions of the tube. At the same time the upper or least accessible side of the guard is left open to provide for rapid dissipation 30 of the heat by the radiating means 31.

40 To increase the protection afforded by the guard portions 32, there is also provided a second guard portion in the form of a metallic or wire frame 36 supported in spaced relation from the first guard portion and tube terminal and having a grounding connection such as continuous contact with the grounded standard of the apparatus. This guard portion is preferably grounded on the stand as more particularly described hereafter at the 45 end opposite the high tension portions while the end of the guard frame adjacent the latter or guard 32 is additionally supported for rigidity by means of an insulating character so that all metal portions of the frame are 50 maintained at a considerable distance from such high tension portions.

The guard frame 36 comprises in the present instance a pair of arcuate strips 37 and 38 connected by wires 39, as shown, and strip 38 55 is further connected by wires 40 with a curved bar 41 embracing the lower side of the tube adjacent the holding frame 11 for the same and having its ends recessed as at 42 to embrace the corresponding clamping bolts 24 of the holding frame. Bar 41 is fixed to the

holding frame in the manner described by the provision of screws 43 adapted to be turned in bosses 44 on the bar to and from clamping engagement with the frame bolt 24 for securely attaching the guard to the tube. The frame thus affords a complete and effective guard about and spaced at a substantial distance from the guard portion 32. The guard frame 36 is additionally supported by spaced struts 45 secured at one end to its strap 38 and at the other to metal sockets 46 anchored in the composition guard 32, struts 45 being preferably constructed of suitable insulating material so that no metal portions of the frame approach the first guard portions or the high tension connections.

It will be noted from the above described construction that the insulating guard portion 32 is rigidly clamped directly to the high tension of the X-ray tube or the usual glass shield tube for the same, and that the conducting guard portion 36 is rigidly secured to the first guard portion 32, and by means of the latter to the high tension end of the tube. Such construction rigidly supports both guard portions to just that portion of the tube, namely the high tension end which is to be protected, so that the impacts of usage, and blows of considerable force cannot derange either guard portion from its proper position. In other words, the guards are rigidly supported at those points where the spacing is important, and so that no impacts can bend them to allow objects to approach dangerously near the high tension conductors. It will furthermore be noted that the conducting guard portion 36 is given an open form of construction through the use of a wire frame so that this portion does not interfere with free circulation of the air which is relied upon to cool the radiating means of the tube.

While the metal guard portion 36 is secured as described to the metal tube holding frame 11 sliding on the metal tube stand, it is preferred to further insure effective grounding of this portion of the guard at all times on the stand by an additional contact to maintain a good electrical connection should the sliding contact between the tube holding frame and stand be rendered resistent by the action of lubrication substance. To this end there is secured to an end of the guard frame bar 41 a conducting leaf spring 47, Figures 3 and 4, arranged to maintain the sliding contact at all times with the lower side of the standard yoke 12 in the sliding movement in the latter of the tube holding frame.

The invention thus provides a doubly effective guard for the high tension portions of the tube capable of being manufactured and assembled in a practical and economical manner and ingeniously adapted in all positions of the tube to maintain a casing of in-

sulating material and in addition a spaced and grounded metal frame between the high tension portions of the tube and objects which might be brought into contact or undue proximity thereto.

We claim as our invention:

1. In X-ray appliances the combination of an X-ray tube, a support for said tube comprising spaced collars and tie rods connecting the same, and a metal guard frame provided with means for adjustably and detachably securing the same to said rods for maintaining an air gap about said tube.
2. In X-ray appliances, the combination of an X-ray tube, a support for said tube comprising spaced collars and tie rods connecting the same, a guard portion of insulating material having a yoke for engagement with said tube to support the same thereon, and a wire frame secured to said guard portion and provided with means for detachably se-

curing the same to said tie rods for maintaining an air gap about said tube.

3. In X-ray appliances, the combination of an X-ray tube having a high tension terminal and heat radiating means at one end thereof, means for supporting said tube, a guard of insulating material constructed to enclose the high tension end of said tube, but open at its top to provide for cooling circulation of air, a split yoke in detachable clamping engagement about said tube end and connected to said insulating guard to rigidly support said guard directly on said tube, and a grounded wire frame rigidly connected by insulating means in spaced relation with said guard to preserve an air gap and provided with means detachably securing the same to said tube support.
